UNITED STATES PATENT OFFICE.

EMIL JENDIS, OF CHICAGO, ILLINOIS.

DESIGN FOR A SHOWER-BATH.

SPECIFICATION forming part of Design No. 27,189, dated June 8, 1897.

Application filed April 21, 1897. Serial No. 633,189. Term of patent 14 years.

To all whom it may concern:

Be it known that I, EMIL JENDIS, a citizen of the United States, residing at Chicago, in the county of Cook and State of Illinois, have 5 invented and produced a new and original Design for Shower-Baths and Like Structures, which is fully set forth in the following specification, reference being had to the accompanying drawings, forming a part here- 10 of, and in which—

Figure 1 is a front view, and Fig. 2 a side or end view, of my said new design for shower-baths.

As shown in the drawings, the leading or 15 material feature of my new design for a shower-bath consists of a four-sided chamber wherein the front and rear walls are rigid and whereof the front wall is ornamented with an oval mirror with ornamental scrolls above 20 and below and on the sides of the mirror executed in any suitable manner, the said side ornaments extending to the lower end of the dresser, which forms the lower part of said front wall. The opposed side walls are 25 duplicate parts of each other, and consist of the same scroll ornamentation at the edges or corners of said walls, a curtain-pole under a scroll-frieze, and a pair of curtains on rings hung from said poles. Said scroll-frieze is 30 surmounted with two plain ogee moldings, which are capped with a leaf-scroll on each

side of a shield surmounted by an eagle in a ring with partly-extended wings, there being also marginal and oval scrolls over said leaf-scrolls on each side of said ring, and on each 35 side of said ring and above the eagle outward-spreading scrolls, and a star on the ring over the eagle. The front part of the side forming the front corner of the dresser is also ornamented with a scroll of like formation as 40 the corners of the chamber. There is a piece of scrollwork near each end of the panel of the dresser, and midway between them and central to the panel is a capital letter "J" within a circular wreath formed of two tapering 45 braids of leaves, which are united at their base by flowing ribbons, leaving the points of the braids partly separated. The bracket-shelves, casters, and other unmentioned parts shown do not form any essential part of my 50 design.

Having thus described my said newly-invented design for shower-baths, I desire to secure said invention by Letters Patent, and I hereby claim the said invention: 55

The design for shower-baths, as herein shown and described.

EMIL JENDIS.
